UNITED STATES PATENT OFFICE

HILLER A. BRIM, OF CHICAGO, ILLINOIS

ROTARY SCRUBBING MACHINE

Application filed January 31, 1929. Serial No. 336,494.

My invention relates in general to improvements in rotary scrubbing machines and has reference to that type of machine in which the scrubbing brushes are attached to a movable or wheeled structure upon which a motor and suitable gearing are provided to rotate the brushes over a surface to be cleaned.

My invention is directed mainly to new and improved means for supporting the brushes and for driving the same.

Among the objects of the invention are to provide an improved form of brush ring for supporting the brushes and retaining them in position; to provide an improved and highly efficient mechanism for supporting and driving the brush ring unit and to generally improve the construction and operation of the machine in such a manner as to facilitate manufacture and render the machine more efficient and effective.

Further objects and features of improvement not specifically mentioned will appear from a reading of the following detailed description.

Fig. 1 is a sectional view of the machine of my invention, being a complete sectional view of the brush ring and driving parts and showing the motor in full.

Fig. 2 is a bottom view of the brush ring structure when removed from the machine.

Fig. 3 is a view looking down on the brush ring assembly when that assembly is removed from the machine.

Fig. 4 is a perspective view of a brush.

Fig. 5 shows a view of the center part of brush ring structure 13 showing the pin 12 and the key ways 14 and 15.

Referring to the above mentioned drawing, I have shown in Fig. 1 a frame or main structure comprising a metal case 1 which has a pair of wheels (only one being shown), one on each side, and a handle which may be attached to bracket 2. This casing 1 has a forward extension 3 of dome shape which supports the brush ring structure. A motor of any well-known type is supported inside the rear end of the casing as shown and fastened to the bottom of the casing by bolts in the customary manner. The shaft 4 of

this motor extends forward and carries a worm on its far end (not shown) which meshes in known manner with a worm gear 5. A water tank of any desired capacity is mounted on the casing above the motor.

The forward end of the casing 3 has in the upper part a bearing 6 and a rib or ring 7. The shaft 8 of the brush ring structure is inserted into the bearing 6 and carries the worm gear 5 rigidly secured thereto. The cup shaped bracket 9 is fastened by screws to the rib or ring 7 of the casing, and supports the entire brush ring structure. In the center of the lower side of this bracket is another bearing for shaft 8, and a packing ring 10, which screws into threads on bracket 9. Both upper and lower bearings of shaft 8 are preferably ball bearings and, as will be understood, the worm on the end of shaft 4 of the motor meshes with worm gear 5 inside bracket 9 to rotate shaft 8. The bracket 9 may be filled with oil as desired for lubrication.

On the lower end of shaft 8 is a ball 11 fastened thereto by screw threads. This ball 11 has a pin 12 passing therethrough and extending for a short distance on each of two sides of the ball. The brush ring structure proper comprises a single casting and has a metal ring 13 having down and inwardly turned edges as clearly shown in Fig. 1. The ring 13 has unitary therewith a metal webbing or horizontal structure formed in special design to act as supports for the brushes, and in the center has a cup-shaped portion acting as a bearing for ball 11. On two sides of the cup are key ways or slots 14 and 15, shown clearly in Figs. 1 and 5, into which the ends of pin 12 are fitted. Each key way allows vertical movement of pin 12 but not lateral movement, the sides of these slots being engaged by pin 11 to communicate rotary movement of shaft 8 to brush ring 13. This construction comprises a universal joint which enables the ring to be rotated with shaft 8 but still allows the brush ring to tilt sideways to a limited extent to take care of unevenness in floors. Above the brush ring is a bracket 16 which is inserted over shaft 8 before the ball 11 is screwed on. This bracket 16, as will be seen, completes the as-

sembly of the joint and by means of the bolts 17 and 18 the brush ring is secured to ball 11, bolts 17 and 18 being riveted in bracket 16.

Referring now especially to Fig. 2 which shows the under side of the brush ring 13, I have shown two brushes held in place in the ring and the means for securing them. There are a pair of studs on the under side of the casting which includes ring 13 at 34 and 35, each of which has a spring clip mounted thereon, as shown, by means of a bolt, washer, and nut. The spring 19, as shown, lies in its normal position and its two ends may be bent together to insert brushes as shown by spring 20 which has been flexed together and then allowed to spring back to hold brushes 21 and 22 in place. Each brush is formed as shown in Fig. 4, the back 23 having one straight edge with a groove 24 running throughout its length and a curved side having a shoulder 25 running throughout its length. As shown, the brush ring structure includes a series of inwardly turned ribs such as 26 and 27 behind which the shoulder 25 of a brush fits. As a further means of locating and holding the brushes, there are the ribs 28, 29, 30, and 31 so placed that one engages the blunt end of the brush back as at 28 and another the flat side near the end. Each rib thus spaces the end and side of two brushes as shown at 29. The spring 20 when allowed to return after the brushes are inserted enters the groove such as 24 of each brush 21 and 22, thus effectively locking two brushes in place. On a stud 32 is a similar spring 33, each end of which engages a groove in the lower end of bolts 17 and 18 to lock them in place and forming a convenient 40 means of removing the brush assembly as a whole from ball 11.

It will be noted that the pointed end of each of the brushes 21, etc., point in the same direction around the circumference of the brush ring structure, and that the structure is rotated in a clockwise direction, referring to Fig. 2, in a manner such as to utilize the shape of the brushes above described to cause the pointed end of each brush to draw washing fluid and powder toward the center of the brush to facilitate cleaning.

It will, therefore, be seen that the assembly including the brush ring 13 and the brushes may be readily removed from the machine and replaced, or each brush may be readily removed and replaced by merely compressing one of the springs 19, 20, or 33. That the machine as a whole has few working parts and is readily accessible for repair and adjustment. Furthermore, the universal joint construction connecting shaft 8 with the brush ring for rotating it is novel in such a machine and comprises a simple and rugged construction giving the ring a side motion so that it can follow unevenness

in floors and yet acting as an interlock so that rotation of the shaft is communicated to the ring without appreciable wear or noise.

Having fully described and ascertained the features and aspects of my invention, what I consider to be new and desire to have protected by Letters Patent will be pointed out in the appended claims.

What is claimed is:

1. In a scrubbing machine, a brush carrier, a vertical shaft, a motor for driving the shaft, the brush carrier secured to the lower end of the shaft and rotated therewith, said brush carrier comprising a unit casting and a plate for securing the casting to the end of the shaft immovable vertically thereon, said carrier and plate having only tilting movement relative to said shaft, a pair of bolts locking the brush carrier and plate to the shaft, and a single spring engaging notches in said bolts to lock the assembly together.

2. In a floor scrubbing machine, a brush carrier comprising a web casting, a plurality of brushes mounted on said casting, each brush substantially triangular in shape with a flat end and a pointed end, said brushes mounted with the pointed ends all pointing in the same direction around the circumference of the carrier, a single spring holding two of said brushes in place, and means for rotating the carrier to move the brushes pointed end first.

In witness whereof, I hereunto subscribe my name this 29th day of January, A. D. 1929.

HILLER A. BRIM.
